LADLE MAINTENANCE SAFETY CAGE WITH MEANS FOR SUSPENDING SPARE STOPPER ROD THEREIN

June H. Reighart, Cleveland, Ohio, assignor to Sticker Industrial Supply Corporation, Cleveland, Ohio, a corporation of Ohio

Application September 13, 1957, Serial No. 683,845

6 Claims. (Cl. 22—85)

The invention relates to maintenance safety cages adapted to be temporarily placed within a ladle such as is used for receiving molten metal from an open hearth or electric furnace and pouring the metal into ingot molds or the like, and more particularly to means for suspending a spare stopper rod in the cage; and the present application is a continuation-in-part of my copending application Serial No. 578,328, filed April 16, 1956, now U.S. Patent No. 2,816,335.

In conventional steel mill practice, molten metal is poured from an open hearth or electric furnace into a ladle having a nozzle in its bottom for pouring the molten metal from the ladle into ingot molds. This nozzle is formed of refractory material and is adapted to be closed by a stopper rod which extends to the top of the ladle and is connected to a gooseneck through which it is operated to control the pouring of molten metal through the nozzle.

The stopper rod is in the form of a metal rod having a stopper head of compressed graphite or the like at its lower end, and having a plurality of refractory sleeves located throughout the length of the rod. This refractory lining of the stopper rod and the refractory nozzle both burn out and must be replaced after the pouring of each heat of metal.

Under usual steel mill practice, it is necessary to wait several hours after the pouring of a heat before the ladle is sufficiently cool to allow a man to enter the ladle in order to replace the burned-out nozzle and stopper rod.

The ladle maintenance safety cage disclosed in my copending application above referred to may be placed in a hot ladle immediately after the metal has been poured therefrom so that a man may immediately enter the safety cage and replace the burned-out nozzle and stopper rod.

This ladle maintenance safety cage comprises generally a refractory lined steel shell adapted to fit within a ladle and having a stopper rod setting well in one side thereof, extending from the top of the cage to the bottom thereof and communicating at its lower end with a working notch in the bottom of the cage through which a workman within the cage may have easy access to the nozzle of the ladle, so as to remove the old burned-out nozzle and place a new nozzle therein.

A platform is located within the cage at a point spaced from the top thereof so that a workman standing upon the platform may disconnect the burned-out stopper rod from the gooseneck of the ladle and mount a new stopper rod therein.

The graphite stopper head upon such stopper rods is very fragile and subject to fracture from impact, which would result in leaking of the molten metal around the broken stopper rod head through the ladle nozzle. For this reason it is necessary that the stopper rods be carefully handled before placing the same in the ladle.

With the use of the safety cage as disclosed in my copending application, the practice has been to first replace the nozzle in the ladle, and then to convey a new stopper rod, by means of a crane or the like, from a distant point

to the safety cage and to position the new stopper rod in the stopper rod setting well of the safety cage so that the workman within the cage may connect the stopper rod to the gooseneck of the ladle.

It frequently happens that at the time the workman in the safety cage is ready for a new stopper rod, that another ladle may be in use at a point between the ladle in which the safety cage is located at the time and the point where the spare stopper rods are stored. This requires a considerable delay until the metal has been poured from said other ladle before a crane can convey a new stopper rod from the storage point to the safety cage.

It is, therefore, an object of the present invention to provide a ladle maintenance safety cage with a stopper rod setting well therein and an open-sided pocket communicating with one side of the stopper rod setting well and extending to a point above the top of the cage for suspending a spare stopper rod therein with the stopper head thereof spaced above the bottom and away from the sides of the cage.

Another object is to provide a ladle maintenance safety cage of the character referred to in which the upper end of the pocket for the spare stopper rod has a top wall provided with a slot through which the upper end of the spare stopper rod extends and from which the spare stopper rod is suspended.

A further object is to provide such a ladle maintenance cage of the character referred to, in which the spare stopper rod is suspended from the upper wall of the pocket by means of the usual nuts which connect the stopper rod to the gooseneck of the ladle.

A still further object is to provide a ladle maintenance safety cage of this type in which a pivoted latch is provided upon the upper wall of the spare stopper rod suspension pocket for preventing accidental displacement of the spare stopper rod from the pocket.

The above and other objects apparent from the drawing and following description, may be attained, the above described difficulties overcome and the advantages and results obtained, by the apparatus, construction, arrangement and combinations, subcombinations and parts which comprise the present invention, a preferred embodiment of which, illustrative of the best mode in which applicant has contemplated applying the principle, being set forth in detail in the following description and illustrated in the accompanying drawing.

In general terms, the invention may be briefly described as comprising a ladle maintenance safety cage in the form of a refractory lined steel shell, shaped to fit within a ladle and having a stopper rod setting well in one side thereof, with a working notch in the bottom of the cage below and in alignment with the stopper rod setting well, and a pocket for suspending a spare stopper rod communicating with one side of the stopper rod setting well and extending to a point above the top of the ladle, with means for suspending a spare stopper rod within said pocket with the stopper head of the rod spaced above the bottom and away from the side walls of the ladle.

This permits a workman within the cage to disconnect the spare stopper rod from the top of the pocket and to move the stopper rod from the pocket into the stopper rod setting well and lower the stopper rod through the working notch in the bottom of the cage into contact with the nozzle of the ladle, and then connect the upper end of the stopper rod to the gooseneck of the ladle.

By way of example, a preferred embodiment of the improved ladle maintenance safety cage with spare stopper rod suspending pocket therein is illustrated in the accompanying drawing, in which;

Fig. 1 is a vertical sectional view through a ladle maintenance safety cage embodying the invention, show-

ing a spare stopper rod suspended within the pocket communicating with the stopper rod setting well, taken on the line 1—1, Fig. 2;

Fig. 2 is a top plane view of the ladle maintenance safety cage shown in Fig. 1, with the access door open and the hinged cover plate in open position;

Fig. 3 is an enlarged top plan view of the spare stopper rod suspension pocket;

Fig. 4 is a fragmentary sectional view of the upper portion of the spare stopper rod suspension pocket, taken on the line 4—4, Fig. 3; and,

Fig. 5 is a fragmentary sectional view of the upper portion of the spare stopper rod suspension pocket taken as on the line 5—5, Fig. 3, showing the upper portion of a stopper rod suspended therein.

Referring now more particularly to the construction illustrated in the drawing, in which similar numerals refer to similar parts throughout, the improved ladle maintenance safety cage forming the subject matter of the invention may be of the general construction as disclosed in my copending application, Serial No. 578,328, above referred to.

This cage comprises a substantially cylindrical metallic shell 10, of substantially the same height as the ladle in which it is to be used, and of proper diameter to permit lowering the cage into the ladle in the manner disclosed and described in detail in my copending application above referred to.

Since the manner in which the safety cage is located within the ladle is illustrated and described in detail in my copending application, it is not thought necessary that the ladle be shown in the present application.

The side walls 11 and bottom wall 12 of the steel shell are provided with a suitable heat insulation lining of brick or the like, as indicated at 13 and 14 respectively. A vertical opening 15 is formed in one side of the cage in the manner illustrated and described in detail in my copending application, and communicates at its lower end with a working notch 16 in the bottom wall of the cage.

A vertical stopper rod setting well 17, comprising a steel shell 18 and refractory insulation 19, communicates with the vertical opening 15 in the side wall of the cage and extends from the top of the cage to a point spaced from the lower end thereof, below which an access door 20 is hinged to one side of the opening 15 as indicated at 21.

A hinged cover 22, which may be in the form of a metal plate, is hinged as at 23 to the lower end of the stopper rod setting well and adapted to be raised against the back wall of the setting well as shown in Figs. 1 and 2 when setting the stopper rod, and dropped into horizontal position upon the top of the access door 20 when setting the nozzle.

When the workman within the cage is removing the old burned-out nozzle from the ladle and placing a new nozzle therein, the access door 20 may be closed and the hinged cover 22 may be lowered into horizontal position upon the top of the door.

When it is desired to set the new stopper rod, the hinged cover 22 is swung upward to open position and the door 20 is swung to open position, entirely clearing the stopper rod setting well, as shown in Figs. 1 and 2. Thus, the door 20 and hinged cover 22 when open, form no obstruction within the cage which might interfere with removal of the burned-out stopper rod or setting of a new stopper rod in the ladle.

An approach platform 24 may be attached to the upper end of the cage and extends radially therefrom, as shown in Figs. 1 and 2, in order to provide safe entrance and exit for the workman to and from the interior of the cage. Hand rails 25 are located on each side of the approach platform at suitable height to be grasped by a workman walking upon the platform.

A short ladder 26 is attached to the inside of the cage, adjacent to the approach platform 24, and extends there-

from down to the stopper rod setting platform 27, located within the cage at a suitable height therein to permit a workman standing on the platform to disconnect the old burned-out stopper rod from the gooseneck of the ladle, and to place a new stopper rod in position in the ladle, through the stopper rod setting well 17.

Angular hand rails 28 are located within the cage, above the stopper rod setting platform 27, with the angular ends thereof disposed toward and on each side of a long ladder 29 attached to the inside of the cage and leading from the top of the cage to the bottom thereof.

A safety chain 30 may be detachably connected to the hand rails 28 when a workman is working on the platform 27, this chain being removable to permit the workman to step from the platform 27 onto the ladder 29.

For the purpose of suspending a spare stopper rod within the cage in position to be easily and readily moved into the stopper rod setting well 17, in order to seat the stopper rod in the nozzle of the ladle, a recess 31 is formed in the side of the stopper rod setting well 17 opposite to the side upon which the access door 20 is hinged, and a channel or U-shape pocket 32, formed of sheet steel or the like, is mounted in the recess 31 and extends to a point above the top of the cage, as best shown in Fig. 1.

A top plate 33 is welded or otherwise attached to the upper end of the pocket 32 and has a slot 34 therein open at the upper side of the pocket 32. This slot is of sufficient diameter to receive the projecting upper end of the steel rod 35 of the stopper rod as best shown in Figs. 1 and 5.

The usual nuts 36 and 37, by means of which the stopper rod is attached to the gooseneck of the ladle, may be tightened against the top and bottom respectively of the top plate 33 of the pocket, as shown in these figures, in order to secure the spare stopper rod, indicated generally at 38, so that the same is suspended within the cage with the graphite stopper head 39 thereof suspended above the bottom wall and away from the side walls of the cage, so that the same is protected against impact or contact with the bottom or sides of the cage.

As a safety precaution, a latch bar 40 may be provided across the slot 34 to prevent accidental displacement of the stopper rod from the pocket 32. This latch bar has a pivot pin 41 at one end extending through an aperture 42 in the top wall 33 of the pocket and is provided with a shoulder or head 43 at its lower end.

At the other end of the latch bar 40, a depending lug 44 is provided, adapted to be received in an opening 45 in the top wall 33. The pivot pin 41 is of considerably greater length than the lug 44, whereby the latch bar 40 may be grasped by the fingers and raised to remove the lug 44 from the aperture 45, the latch bar 40 then being swung upon the pivot pin 41 to clear the slot 34 in the top plate 33 in order to permit the spare stopper rod to be removed from the pocket 32.

After the workman has removed the old burned-out stopper rod and replaced the burned-out nozzle in the ladle, the latch bar 40 may be swung to open position and the nuts 36 and 37 upon the stopper rod may be loosened so that the workman, standing upon the platform 27, may move the spare stopper rod 38 laterally out of the pocket 32 onto the stopper rod setting well 17 and gently lower the stopper rod so that the stopper head 39 thereof is seated upon the nozzle in the ladle.

The upper end of the threaded rod 35 of the stopper rod may then be attached to the gooseneck of the ladle, by means of the nuts 36 and 37, in conventional manner, after which the cage may be removed from the ladle and the ladle is again ready for use.

It will thus be apparent that the improved ladle maintenance safety cage with suspension means for a spare stopper rod provides an additional improvement and advantage in setting a new stopper rod in a ladle. With the pocket in one side of the stopper rod setting well of the cage, the spare stopper rod is suspended in position to

protect the stopper head thereon, and in position where it is easily accessible to the workman within the cage, so that it may be quickly and easily moved from the pocket into the stopper rod setting well and properly set in the nozzle of the ladle and attached to the gooseneck of the ladle.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiments of the improved construction illustrated and described herein are by way of example, and the scope of the present invention is not limited to the exact details of construction.

Having now described the invention or discovery, the construction, the operation, and use of preferred embodiments thereof, and the advantageous new and useful results obtained thereby; the new and useful construction, and reasonable mechanical equivalents thereof obvious to those skilled in the art, are set forth in the appended claims.

I claim:

1. A ladle maintenance safety cage for protecting a human operator from the heat of a ladle used for molten metal and having a nozzle in its bottom and a stopper rod controlling said nozzle, said cage comprising a steel shell adapted to be inserted into the ladle, a heat insulation lining within said shell, there being a vertical opening in one side of the cage extending from the top of the cage to the bottom thereof, a stopper rod setting well in said one side of the cage and adapted to accommodate the stopper rod in the ladle, said well extending from the top of the cage to a point spaced from the bottom thereof and comprising spaced vertical side walls extending inwardly from opposite edges of said vertical opening and a vertical back wall connected to the inner edges of said side walls, there being a working notch in the bottom of the cage communicating with the lower end of said vertical opening and providing access to the nozzle in the ladle, a vertical pocket in one side wall of said well, and means for suspending a spare stopper rod in said pocket with the lower end of the spare stopper rod spaced above the bottom of the cage, whereby the spare stopper rod may be moved laterally from said pocket into the well and inserted through said working notch into engagement with the nozzle of the ladle.

2. A ladle maintenance safety cage for protecting a human operator from the heat of a ladle used for molten metal and having a nozzle in its bottom and a stopper rod controlling said nozzle, said cage comprising a steel shell adapted to be inserted into the ladle, a heat insulation lining within said shell, there being a vertical opening in one side of the cage extending from the top of the cage to the bottom thereof, a stopper rod setting well in said one side of the cage and adapted to accommodate the stopper rod in the ladle, said well extending from the top of the cage to a point spaced from the bottom thereof and comprising spaced vertical side walls extending inwardly from opposite edges of said vertical opening and a vertical back wall connected to the inner edges of said side walls, there being a working notch in the bottom of the cage communicating with the lower end of said vertical opening and providing access to the nozzle in the ladle, a vertical pocket in one side wall of said well, and means at the upper end of said pocket for suspending a spare stopper rod in said pocket with the lower end of the spare stopper rod spaced from the bottom and sides of the cage, whereby the spare stopper rod may be moved laterally from said pocket into the well and inserted through said working notch into engagement with the nozzle of the ladle.

3. A ladle maintenance safety cage for protecting a human operator from the heat of a ladle used for molten

metal and having a nozzle in its bottom and a stopper rod controlling said nozzle, said cage comprising a steel shell adapted to be inserted into the ladle, a heat insulation lining within said shell, there being a vertical opening in one side of the cage extending from the top of the cage to the bottom thereof, a stopper rod setting well in said one side of the cage and adapted to accommodate the stopper rod in the ladle, said well extending from the top of the cage to a point spaced from the bottom thereof and comprising spaced vertical side walls extending inwardly from opposite edges of said vertical opening and a vertical back wall connected to the inner edges of said side walls, there being a working notch in the bottom of the cage communicating with the lower end of said vertical opening and providing access to the nozzle in the ladle, a vertical pocket in one side wall of said well, said pocket comprising a generally channel shape member extending above the top of the cage, and means at the upper end of said pocket with the lower end of said spare stopper rod spaced from the bottom and sides of the cage, for suspending a spare stopper rod in said pocket, whereby the spare stopper rod may be moved laterally from said pocket into the well and inserted through said working notch into engagement with the nozzle of the ladle.

4. A ladle maintenance safety cage for protecting a human operator from the heat of a ladle used for molten metal and having a nozzle in its bottom and a stopper rod controlling said nozzle, said cage comprising a steel shell adapted to be inserted into the ladle, a heat insulation lining within said shell, there being a vertical opening in one side of the cage extending from the top of the cage to the bottom thereof, a stopper rod setting well in said one side of the cage and adapted to accommodate the stopper rod in the ladle, said well extending from the top of the cage to a point spaced from the bottom thereof and comprising spaced vertical side walls extending inwardly from opposite edges of said vertical opening and a vertical back wall connected to the inner edges of said side walls, there being a working notch in the bottom of the cage communicating with the lower end of said vertical opening and providing access to the nozzle in the ladle, a vertical pocket in one side wall of said well, a top plate on the pocket having a slot therein for receiving the upper end of a spare stopper rod located in said pocket, and means for attaching the upper end of the spare stopper rod to said top plate with the lower end of said spare stopper rod spaced from the bottom and sides of the cage, whereby the spare stopper rod may be moved laterally from said pocket into the well and inserted through said working notch into engagement with the nozzle of the ladle.

5. A ladle maintenance safety cage for protecting a human operator from the heat of a ladle used for molten metal and having a nozzle in its bottom and a stopper rod controlling said nozzle, said cage comprising a steel shell adapted to be inserted into the ladle, a heat insulation lining within said shell, there being a vertical opening in one side of the cage extending from the top of the cage to the bottom thereof, a stopper rod setting well in said one side of the cage and adapted to accommodate the stopper rod in the ladle, said well extending from the top of the cage to a point spaced from the bottom thereof and comprising spaced vertical side walls extending inwardly from opposite edges of said vertical opening and a vertical back wall connected to the inner edges of said side walls, there being a working notch in the bottom of the cage communicating with the lower end of said vertical opening and providing access to the nozzle in the ladle, an access door hingedly connected to one edge of said vertical opening below the well, a vertical pocket in the side wall of said well opposite to said access door, and means for suspending a spare stopper rod in said pocket with the lower end of said spare stopper rod spaced from the bottom and sides of the cage, whereby

the spare stopper rod may be moved laterally from said pocket into the well and inserted through said working notch into engagement with the nozzle of the ladle.

6. A ladle maintenance safety cage for protecting a human operator from the heat of a ladle used for molten metal and having a nozzle in its bottom and a stopper rod controlling said nozzle, said cage comprising a steel shell adapted to be inserted into the ladle, a heat insulation lining within said shell, there being a vertical opening in one side of the cage extending from the top of the cage to the bottom thereof, a stopper rod setting well in said one side of the cage and adapted to accommodate the stopper rod in the ladle, said well extending from the top of the cage to a point spaced from the bottom thereof and comprising spaced vertical side walls extending inwardly from opposite edges of said vertical opening and a vertical back wall connected to the inner edges of said side walls, there being a working notch in the bottom of

the cage communicating with the lower end of said vertical opening and providing access to the nozzle in the ladle, a vertical pocket in one side wall of said well, a top plate on the pocket having a slot therein for receiving the upper end of a spare stopper rod located in said pocket, means for attaching the upper end of the spare stopper rod to said top plate, and a pivoted latch bar on said top plate for locking the upper end of the spare stopper rod in said slot with the lower end of said spare stopper rod spaced from the bottom and sides of the cage, whereby the spare stopper rod may be moved laterally from said pocket into the well and inserted through said working notch into engagement with the nozzle of the ladle.
